UNITED STATES PATENT OFFICE.

JAMES D. ROSS, OF SEATTLE, WASHINGTON.

DESIGN FOR A LAMP-CLUSTER.

42,859.

Specification for Design.

Patented Aug. 6, 1912.

Application filed May 29, 1912. Serial No. 700,530. Term of patent 7 years.

To all whom it may concern:

Be it known that I, JAMES D. Ross, a citizen of the United States, residing at Seattle, in the county of King and State of Washington, have invented a new, original, and ornamental Design for a Lamp-Cluster, of which the following is a specification, reference being had to the accompanying drawing, forming part thereof.

The figure is a side elevation showing my

design of lamp cluster as it appears when mounted upon a pole, or standard, or other suitable support.

I claim:

The ornamental design for a lamp cluster, as shown.

JAS. D. ROSS.
